his ATTORNEYS

UNITED STATES PATENT OFFICE.

JOSEPH S. THOMPSON, OF SAN FRANCISCO, CALIFORNIA.

LATCH FOR ELECTRIC SWITCHES.

Application filed May 11, 1925. Serial No. 29,283.

To all whom it may concern:

Be it known that I, JOSEPH S. THOMPSON, a citizen of the United States, and a resident of the city and county of San Francisco, State of California, have invented certain new and useful Improvements in Latches for Electric Switches, of which the following is a specification.

This invention relates to latches for electric switches. More particularly it relates to latches for electric switches of the knife or blade type. In switches of this character it is desirable to lock the same in their closed position, not only to insure a good contact but to prevent their opening at undesired times. This is particularly true where the switches are mounted on moving bodies or are in other positions subject to vibration.

An object of the invention is to provide an improved device of this character which is of rugged and simple construction and which will operate in a safe and reliable manner.

The invention possesses other advantageous features, some of which with the foregoing will be set forth at length in the following description, where I shall outline in full that form of the invention which I have selected for illustration in the drawings accompanying and forming part of the present specification. In said drawings I have shown a form of device embodying my invention but it is to be understood that I do not limit myself to such form since the invention as set forth in the claims may be embodied in a plurality of other forms.

In the drawings:

Figure 1 is a side elevation of a switch embodying my invention with the latch shown in closed position.

Fig. 2 is a section taken on the line 2—2 of Fig. 1, and

Fig. 3 is a section taken on the line 3—3 of Fig. 1 but also showing a switch opening member and the switch in open or unlocked position.

Referring to the drawings in which 1 indicates a base which supports a pair of fixed contacts 2, 2 in the usual manner. The base 1 also supports a fixed lug 3 which cooperates with my improved latch as will hereinafter be described. The lug 3 is preferably positioned on the parts supporting the contacts 2, 2, as shown although it is ob-

vious that this lug could be placed in numerous other positions on the base 1. The numeral 4 indicates a switch blade which is pivotally connected to a terminal in a manner readily understood and not shown in the drawings. The free end of the switch blade 4 which extends beyond the contacts 2, 2 is provided with my improved latch mechanism which consists of a ring 5 or other suitable member having a central opening which is riveted or otherwise suitably secured to the said blade as indicated at 6 in Fig. 1. The ring 5 is shown in section in Fig. 2 and its inner periphery is indicated in dotted lines in Fig. 1. At its edge opposite the rivets 6 the ring is provided with suitable lugs or ears 7 on which a door 8 is pivoted or hinged. The door 8 preferably has a solid surface, is substantially the same size as the ring 5 and is pivoted to said ring by means of a bolt 9 in a manner readily understood. A spring 10 is provided normally to urge the door against the ring 5 or in its closed position. The door 8 swings inwardly toward the lug 3 on its hinge in a plane at right angles to the movement of the blade 4 about its pivot. On its surface adjacent the ring 5 the door 8 is preferably provided with a lug 11 which passes over the inner periphery of said ring and assists in positioning and holding the door in its closed position. The door 8 is also provided with a hook or latch member 12 as shown in Fig. 2 which is arranged to pass underneath the lug 3 and thereby lock the blade 4 in its closed position as shown in Fig. 1. In Fig. 3 the door is indicated in its closed position by dotted lines and in its open position by full lines. When the switch is in its closed position, as shown in Fig. 1, the same may be opened by means of an opening member 13, shown in Fig. 3. The member 13 is inserted through ring 5, thereby engaging the door 8 and swinging the same upon its hinge, which disengages latch 12 from lug 3, and unlocks the switch, which may then be pulled open, or thrown to its opposite position, if the switch is of the double throw type. It is of course apparent that my invention is equally adaptable for double throw switches, in which case the other set of fixed contacts is also provided with a lug similar to lug 3, and the door 8 is provided with another latch 12 to cooperate with said lug.

What I claim and desire to secure by United States Letters Patent is:

1. A device of the character described comprising a pivoted switch blade, cooperating fixed contacts therefor and means for locking said blade in closed position on said contacts comprising a fixed element and a hinged catch carried on the free end of said blade adapted to swing in a plane at right angles to the movement of said blade and engage said element.
2. A device of the character described comprising a base, a switch blade pivoted thereon, cooperating fixed contacts on said base positioned intermediate the pivot of said blade and its free end, a fixed element on said base intermediate said contacts and the free end of said blade, and a hinged catch carried on the free end of said blade adapted to swing in a plane at right angles to the movement of said blade and engage said fixed element thereby locking said blade in closed position on said contacts.
3. A device of the character described comprising a pivoted switch blade, cooperating fixed contacts therefor and means for locking said blade in closed position comprising a fixed element independent of said blade and latching means carried on the free end of said blade comprising a ring-formed element secured to the free end of said blade and a member pivoted on said ring-formed
4. A device of the character described comprising a pivoted switch blade, cooperating fixed contacts therefor and means for locking said blade in closed position comprising a fixed element independent of said blade and latching means carried on the free end of said blade comprising a ring-formed element secured to the free end of said blade and a member pivoted on said ring-formed element arranged to swing inwardly over said ring-formed member having a projection adapted to engage said fixed element.
5. A device of the character described comprising a pivoted switch blade, cooperating fixed contacts therefor and means for locking said blade in closed position comprising a fixed element independent of said blade and latching means carried on the free end of said blade comprising a ring-formed element secured to the free end of said blade and a member pivoted on said ring-formed element arranged to swing inwardly over said ring-formed member in a plane at right angles to the movement of said blade having a projection adapted to engage said fixed element.

In testimony whereof, I have hereunto set my hand.

JOSEPH S. THOMPSON.
